FILTER AND HEAT EXCHANGER

Robert Nash Burekhalter and James Marshall Osburn, Michigan City, Ind., assignors to Michiana Products Corporation, a corporation of Indiana

Application July 21, 1932, Serial No. 623,787

11 Claims. (Cl. 210—165)

The principal object of this invention is to facilitate the manufacture of oil filters for use separately or in combination with heat exchangers and, in the main, this is accomplished by means 5 of a casting that will form the base of an oil filter, or a heat exchanger, or the bases or common base of an oil filter and a heat exchanger, and will provide oil connections and by-passes whereby the flow is directed to suit the varying 10 conditions.

Further objects and advantages of the invention will be revealed as the disclosure proceeds and the description is read in connection with the accompanying drawings showing specific forms designed to meet selected requirements for heating 15 cooling and filtering oil in conventional internal combustion engines.

Fig. 1 is a diagrammatic side elevation of a conventional internal combustion engine equipped according to this invention;

Fig. 2 is a vertical section through a commercial unit comprising a heat exchanger and an oil filter;

Fig. 3 is a vertical section of the same taken on the line 3—3 of Fig. 2;

Fig. 4 is a plan view of the unit with the water connections broken away;

Figs. 5 and 6 are transverse sections taken on the lines 5—5 and 6—6, respectively, of Fig. 2;

Figs. 7 and 8 are vertical sections taken on the lines 7—7 and 8—8, respectively, of Fig. 6;

Figs. 9 and 10 are sections similar to Figs. 2 and 6, showing the same base assembled to form an oil filter only, and illustrating a different connection for the outlet of oil;

Figs. 11 and 12 are perspective views of the base casting shown separately;

Fig. 13 is a plan view of the same; and

Figs. 14 and 15 are plan and elevation of a modified form of base casting.

But these drawings and the specific description that follows are used for the purpose of disclosure only, for the substance of the invention may be embodied in many other forms.

General description

Fig. 1 shows an internal combustion engine 10 equipped with a radiator 11 and a pump 12 for circulating cooling water through the radiator and the cylinder jackets 13. The commercial unit supplied by this invention includes a base casting 14, surmounted by a heat exchanger 15 for the lubricating oil, which is connected in series with an oil filter 16, depending from the base 14. The heat exchanger 15 is also connected in series

with the water cooling system by the pipes 17 and 18, whereby the oil in the lubricating system and the water in the cooling system interchange heat.

Specific description

The base casting is best shown separately in Figs. 11, 12, and 13, although the internal formation is illustrated in Figs. 2 to 8. As best shown in Fig. 11, its top is formed by a flange 19 machined to a finished surface on the top. As best shown 10 in Fig. 12, its bottom is a grooved circular flange 20 surrounding a centrally threaded boss 21.

The body portion of this base is provided with a centrally located bore 22 to receive a bolt 23 (Figs. 3 and 6) having its threaded inner end 24 received in a reenforced portion 25 of the engine casing. In effect, this bolt becomes a stud projecting from the casing upon which the base casting is mounted and made fast by a cap nut 26.

The base 14 is drilled and tapped at 27 (at the right in Figs. 2 and 6) to receive a nipple 28, by which oil from the pump is led into the treating apparatus. The inlet thus formed is turned vertically by a bore 29 (Figs. 2 and 11) leading out 20 through the top of the base to the heat exchanger.

The heat exchanger element 30 selected for this illustration resembles the familiar honeycomb radiator in that it is composed of hexagonal tubes 31 enlarged and soldered together at their ends 32, and wrapped in a shell 33, which also forms headers 34 at each end, serving to distribute oil to the narrow meandering passages between the tubes.

The heat exchanger element is mounted within 35 a housing comprising a generally six-sided box, the bottom 35 of which is machined to fit the top of the base 14, where it is held by bolts 36. The left end 37 (Fig. 2) of the housing is made removable to permit the heat exchanger element 40 to be inserted. Both this removable end and the opposite fixed end 38 of the housing are provided with machined pads 39 perforated to receive studs 40 fixed to the headers 34, and equipped with nuts 41, by which the heat exchanger element 45 is made fast within the housing.

The front 42 (Figs. 1 and 3) of the housing is provided with a machined pad 43 to make connection with the inlet pipe 17 for water, and the top 44 has a similar pad 45 for connection with 50 the outlet pipe 18.

The vertical bore 29 of the base communicates with a registering vertical bore 46 (Fig. 2) in the heat exchanger housing, which is continued through a horizontal bore 47 and a vertical bore 55

48, to an opening 69 leading into the right header 34 (Fig. 2). An opening 58 leading out of the left header 34, communicates with the vertical passage 51 in the removable end 31 which has a 5 lateral section registering with the horizontal bore 52, terminating in the vertical bore 53, which registers with a vertical bore 54, leading through the base 16, to communicate with the filter proper.

10 16 The filter includes a shell or casing 55 having its upper end received within the groove of the flange 20, where it is secured by a cap nut 56 threaded onto a tube 57, the upper end of which is seated in the threaded boss 21 of the base.

15 16 The filter element is illustrated as a barrel-shaped screen 58 extended between two headers 59 carried by the tube 57. The form of the filter element and also the heat exchanger element is not the essence of this invention, and for that reason 20 details are omitted. It will be sufficient to say that oil to be filtered enters the casing at the outside, passes through the filter element into the perforated tube 57. The upper end of this tube 25 communicates with a counter bore 60 in the base casting, and this, in turn, communicates with an outlet bore 61, (Fig. 6), tapped to receive the nipple 62 by which the oil connection is made to the bearing header, or such other point of delivery as is desired.

30 30 From this description it follows that oil delivered from the pump enters through the nipple 28 (Figs. 2 and 6), rises through the bores 29, 46, and 48 (Fig. 2), to the heat exchanger element 38, which delivers it through the bores 51, 52, 53, and 35 35 56, to the filter chamber at the outside of the filter element 58. Passing through this to the tube 57, the oil rises into the counter bore 60 and passes through the outlet 61 to the nipple 62, from whence it is led to the desired point of delivery.

40 40 The water is drawn from the bottom of the radiator 11 and forced into the housing of the heat exchanger 15 at the front where it first passes downwardly (Fig. 3) and then upwardly through the tubes of the heat exchanger element, 45 and thence out at the top, to the cylinder jackets.

In order to provide a by-pass for shunting out the heat exchanger when, for any reason, the resistance therein becomes too great, the base casting is provided at the right (Fig. 6) with a horizontal bore 63, communicating with the vertical bore 29, and also another vertical bore 64, leading directly into the filter casing. A ball valve 65 normally held against a seat 66 by a spring 67 adjustably compressed by a screw 68, normally 50 55 60 65 70 prevents flow from the bore 29 to the bore 64, but when the difference in pressure at the opposite sides of the heat exchanger reaches a predetermined value, the valve 65 will be unseated, and the oil will flow directly from the inlet nipple 28 to the filter without passing through the heat exchanger.

At the left (Fig. 6) the base is also provided with a bore 69, connecting the vertical bore 54 with a horizontal bore 71 to shunt oil directly 65 69 75 from the filter casing to the counter bore 60 and, hence, permit the flow from the pump to the bearings without passing through the filter element. This by-pass is normally closed by a ball valve 72 held on a seat 73 by a spring 74, adjustable to 70 suitable compression by a screw 75.

Thus it is seen that either the heat exchanger, or the filter, or both, may be shunted out according to the conditions obtaining in the system.

In some instances the engine maker wishes to 75 buy an oil filter and, at the same time, make pro-

vision for later introducing a heat exchanger into the system. With the construction thus far described this is readily accomplished, as shown in Fig. 9, where the heat exchanger in its entirety is replaced by a plate 76 which closes the passages 29 and 54 in the base casting 16. The effect is the same as if the heat exchanger element was clogged, hence, the by-pass at the right in Fig. 6 leads the entering oil into the filter, through which it passes in the normal way, and then continues to the bearings. When the engine maker is ready for the heat exchanger all that is necessary is to remove the plate 76 and substitute the heat exchanger, as shown in Figs. 2 and 3.

10 15 Where constant use of the by-pass is objectionable plate 76 can have a passage connecting 29 and 54 (Fig. 2).

20 20 In Figs. 9 and 10 there is also shown a variation in the outlet connection, the passage 61 and the nipple 62 being omitted, and the main securing bolt 23 being provided with a central bore 77 communicating through openings 78 with the counter bore 60 of the base casting. This bore 77 can be connected by internal piping or internal 25 passages, with the bearing header, or any other point of delivery.

25 30 While the use of a single bolt to secure the filter or the combined filter and heat exchanger in place on the engine tends to great simplicity, in some instances a plurality of bolts will be desired. Figs. 14 and 15 show a modification of the base casting to meet this situation. The modification consists chiefly in providing perforated flanges 79 to receive bolts for clamping the machined surface 80 against a machined pad, (not 35 shown) on the engine casing, or other support.

35 40 The arrangement of the passages and by-passes is substantially the same as in the other form, except that the central bore 34 may be used for an outlet and the lateral bore 82 may be used for 40 an inlet, whereby all exposed piping for oil is eliminated.

45 50 In some instances a purchaser will desire a heat exchanger with provision for adding a filter later, in which case the housing for the heat exchanger can be mounted on the base casting, as illustrated in Figs. 2 and 3, and the filter replaced by a closing plate made fast by a bolt threaded into the boss 21. Installing the filter later then becomes a simple matter by removing this bolt and closure 50 and inserting the tube 57 with the attached filter parts.

55 55 Where the heat exchanger alone is desired the lower portion of the pattern of the base casting 16 may be replaced by a solid block, and further 55 simplicity may be had by connecting such a pattern directly to the pattern for the housing of the heat exchanger whereby the base and the housing could be cast in one piece.

60 It will be apparent that the invention makes 60 production of combined filters and heat exchangers, or filters, or heat exchangers, a very simple matter.

65 The particular form shown was designed to obtain simplicity and compactness under one set of conditions. Other conditions will warrant appropriate changes. Even a desire to have filtered oil only in the heat exchanger would justify considerable rearrangement, and putting the filter on top would be of advantage in cold weather.

70 75 We claim as our invention:—

1. In an oil treating apparatus, a base casting having inlet and outlet passages, an interior chamber communicating with the outlet passage and a vertical through passage, a heat exchanger

mounted above the base and having inlet and outlet passages registering, respectively, with the inlet and through passages of the base, and a filter attached to the lower face of the base and receiving from its through passage and discharging into its interior chamber.

2. In oil treating apparatus, a base casting having passages for oil, a heat exchanger element having upwardly extending passages for water 10 and laterally extending passages for oil, a casing for the element mounted on top of the base, and having oil passages connecting the oil passage in the element with those in the base and having water passages communicating with those in the 15 element.

3. In an oil treating apparatus, in combination, a base, adapted for attachment to a support, a casing mounted on the base and having an inlet and an outlet for water, a heat exchanger element 20 interposed between such inlet and outlet and having through juxtaposed oil and water passages, ducts incorporated in the casing for leading oil to and from the element, an oil filter carried by the base, the base having an inlet for oil communicating with the leading-in oil duct of the casing, a duct connecting the leading-out oil duct of the casing with the filter, and an outlet for oil 25 communicating with the filter.

4. In oil treating apparatus, a base, a heat exchanger carried on the base above and comprising a housing having an inlet and an outlet for water, a heat exchanger element within the housing having surfaces exposed to water and other surfaces exposed to oil to be treated, a filter carried 30 by and below the base and comprising a casing and an oil filter element therein, the base and housing providing passages for oil to circulate through the heat exchanger and the filter in series, the base also having by-passes across the 35 heat exchanger and the filter.

5. In oil treating apparatus, a base having inlet and outlet passages for oil, a heat exchanger comprising a housing rising from the base, having one end open and provided with an inlet for water 45 adjacent its bottom and an outlet for water at the top, a heat exchanger unit within the housing, and having passages for oil to flow in at one end and out at the other, and passages for water transverse to the passages for oil, a closure for the 50 open end of the housing having an oil passage communicating with the oil passages in the heat exchanger element, the closed end of the housing having a cored passage leading to the opposite end of the exchanger element, both of the last- 55 named oil passages communicating with the oil passages of the base.

6. In an oil treating apparatus, a base plate for attachment to a support, a heat exchanger attached to one face of the plate and having independent oil and water passages therethrough, a filter attached to the opposite face of the plate, the plate being ported for the admission of oil 60

from outside the apparatus and its delivery to one of the attached devices, for the transfer of oil from such device to the other attached device and for its discharge from such device to the exterior of the apparatus.

7. In an oil treating apparatus, a base having induction and eduction oil passages for admitting oil directly from and discharging oil directly to the exterior of the apparatus respectively, a heat exchanger comprising a housing carried by the 10 base and having inlet and outlet ports for water and passages in its walls communicating with the named base passages, and a heat exchanger unit within the casing interposed between the water ports thereof and having water passages and oil 15 passages, its oil passages communicating with the oil passages of the casing.

8. A base adapted for direct attachment to a supporting wall and having a pair of oppositely directed faces, and lateral oil receiving and discharge passages, other passages communicating respectively with the receiving and discharge passages and leading, respectively, through such faces, and a through passage, the opposite faces of the base being adapted for attachment thereto 20 of oil treating elements cooperating with the through passage and, respectively, with the receiving and discharge passages.

9. In an oil treating apparatus, a base plate adapted to be attached to a support and having 30 ports for admitting oil to the apparatus and discharging oil from the apparatus, a heat exchanger and a filter attached to opposite faces of the plate, passages leading from the oil-admitting port through one of the attached members to the other member, and passages in the plate leading 35 from the last-mentioned member to the oil discharge port.

10. A base adapted to be attached to a supporting wall and having a pair of oppositely 40 facing surfaces providing areas adapted to have oil treating elements secured thereto, a passage through the base within said areas adapted to place said elements in communication, an oil inlet port and an oil outlet port in portions of the base outside of said areas, and passages in the base opening through said areas and communicating with said ports.

11. A base adapted to be attached to a supporting wall and having a pair of oppositely facing surfaces providing areas adapted to have oil 50 treating elements secured thereto, a passage through the base within said areas adapted to place said elements in communication, an oil inlet port and an oil outlet port in portions of the base outside of said areas, a passage in the base opening through one of said areas and communicating with one of said ports, and a separate passage in the base opening through the other area and communicating with the other port.
